UNITED STATES PATENT OFFICE.

THEODORE SCHMIDT, OF DAYTON, OHIO, ASSIGNOR OF ONE-HALF TO
HENRY H. LAUBACH, OF SAME PLACE.

OYSTER-BUCKET.

SPECIFICATION forming part of Letters Patent No. 358,411, dated February 22, 1887.

Application filed December 3, 1886. Serial No. 220,557. (No model.)

To all whom it may concern:

Be it known that I, THEODORE SCHMIDT, a citizen of the United States, residing at Dayton, in the county of Montgomery and State of Ohio, have invented a certain new and useful Improvement in Oyster-Buckets; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to improvements in paper vessels known as "oyster-buckets;" and it consists of the formation of the lid with a view to prevent a collapsing of the sides of the vessel, the lid being stiffened by transverse bends of the ends. The object is to prevent the bending in of the top of the vessel while the same is being carried, and this is effectually done by the stiffening of the ends of the lid, which is placed within the top beneath the ends of the bail.

The device as a whole, and in detail, is illustrated in the accompanying drawings, in which—

Figure 1 is a view of the blank. Fig. 2 is a side view of the oyster-bucket. Fig. 3 is a top view of the lid.

Like letters designate like parts throughout the several views.

A is a single piece of paper in outline of the form shown at Fig. 1, and which forms the body of the vessel. The lines drawn across the face of this figure are creases, forming the lines on which the paper is bent. Both sides are folded alike. The parts *c* and *d* are folded together, and then folded against the sides *b*, as indicated by the dotted lines, Fig. 1. The

rectangle at the center forms the bottom of the vessel. The sides and folds are pierced to receive the hooked ends of the bail D.

The vessel has no creasing between the ends *e* and the side folds, *d*.

E is the lid, which has sides each forming arcs of a circle, and ends each forming arcs of less diameter. At the intersection of these latter arcs lines are drawn showing the creasing. At these lines the parts *g* *g* are bent up at a right angle, or inclining to lie closely against the ends of the vessel, which are slightly inclined, as shown at *g*, Fig. 2. The effect of this is to stiffen the lid laterally. When the vessel is filled, the lid is put into the top and pressed beneath the ends of the bail, which holds the lid from rising from its position, and as a pull on the bail by the weight tends to collapse the sides, the bent-up ends stiffen the lid and prevent such collapse. The notches *g* *g*, formed at the intersection of the arcs forming the outline of the lid, engage between the folds *c* and *d* of the bucket, and the circular bands lie against the ends of the bucket and close the top of the vessel very snugly.

Having fully described my invention, what I desire to secure by Letters Patent is—

The vessel constructed as described and provided with a bail and with lid E, having sides formed as arcs of a circle, and creased transversely and bent at the creases to form ears *g* *g*, as and for the purpose set forth.

In testimony that I claim the foregoing as my own I affix my signature in presence of two witnesses.

THEODORE SCHMIDT.
